ROLLER REEFING GEAR

Bror Tamm, Quincy, Mass., assignor to George Lawley & Son Corporation, Neponset, Mass., a corporation of Massachusetts

Application April 14, 1937, Serial No. 136,811

3 Claims. (Cl. 114—107)

My present invention is a novel and improved apparatus providing a roller reefing gear for fore-and-aft rigged vessels, and is directed to improve and perfect the construction and operation of a roller reefing gear at each end of the rotating boom or spar, and comprises novel fittings at the mast end for the tack of the sail and at the outhaul end for the clew of the sail to be rolled upon such boom or spar.

Heretofore various devices constituting roller reefing structures have been devised wherein gears, or the like, have been attached to a boom or similar sail-supporting structure constructed to be rotated to wind the sail around the boom for reefing or furling; but all such prior roller reefing gears have been unsatisfactory in various particulars, being complex, cumbersome, clumsy, difficult to operate and inconvenient in position.

A further difficulty with such prior devices was that the shackle or fastening means for the tack of the sail, where it was secured on the boom, was spaced so far from the mast on which the luff of the sail would slide that it was extremely difficult to operate the roller reefing mechanism as the sail was lowered on the mast during the rolling operation with the sail drawn or pulled at an angle from the fastenings at or around the mast, and an extra hand was required at the mast end to lead the sail into position; and also it was practically impossible to effect a smooth rolling reefing operation because of the angular drag of the luff of the sail from the mast to the boom.

Such operation was especially difficult where slide fastenings were arranged for the luff of the sail and the mast, such slides having to be removed from the track on the mast at a suitable distance above the boom to allow for such angular drag of the luff of the sail between the rolling boom and the slide fasteners.

In my present improved construction I have eliminated the difficulties above briefly outlined and have devised a strong, simple, and efficient rolling reefing gear construction both at the mast end and at the outhaul end, in combination with a goose neck structure which operates to support the boom and roller gears in such a position as to permit the tack of the sail secured to the boom to be substantially in alignment with the goose-neck pivot on which the boom swings and substantially in correct alignment with the luff of the sail.

Thus my present invention provides a roller reefing gear construction and fitting which will draw the luff of the sail during the rolling or

unrolling to the boom shackle, or fastening, for the tack, substantially in direct alignment with the track and slides on the boom, or the encircling mast hoops, when the latter are used, thus eliminating the angular drag between the rolling boom and the mast fastenings and, furthermore, insuring a smooth, even rolling and, hence, reefing and furling operation, entirely automatic and by the simple rotation of the reefing gears and slackening of the hoisting halyards.

Also, I provide this entire improved structure with a novel L-shaped type of goose neck to bring the pivot clews to the mast and with a rotating gear structure in a more compact, strong, and easily operated construction than has heretofore been possible, as well also as providing a fitting at the mast which will guide the sail and guard the gears, and permit the entire fitting to be raised and lowered in any position desired, while at all times keeping the goose-neck boom pivot, tack fastening, and mast slides or fastenings for the luff of the sail substantially in alignment.

In carrying out my invention I provide a rotatable boom structure supported at each end and with a suitable gear adjacent the goose-neck end secured to the boom, together with an operating worm meshing in said gear, to which cranks or handles may be attached for rotating the same, and all supported from my improved and novel goose neck structure which carries the pivotal support for the boom, suitable links holding the worm in mesh with the gear on the boom, and all constructed, arranged, and pivotally supported on an adjustable mast fitting so that the same can be conveniently operated at any angle or position in which the boom may be swung for rolling the boom and reefing the sail or for unrolling the same. This capacity is an important feature and, furthermore, the entire structure is so compact and it requires but slight room and enables the tack of the sail to be fitted on the boom in alignment with both the luff of the sail on the mast and the pivot of the boom for swinging vertically and horizontally.

In combination with this improved mast structure I provide a novel and improved clew outhaul structure which cooperates therewith.

Referring to the drawings illustrating a preferred embodiment of my invention,

Fig. 1 is a diagrammatic plan view;

Fig. 2 is an enlarged cross-sectional view of the clew out-haul end;

Fig. 3 is a fragmentary view in cross-section of the clew outhaul structure;

Fig. 4 is a cross-sectional view on the line 4—4 of Fig. 3;

Fig. 5 is a cross-sectional view on the line 5—5 of Fig. 3 showing the slide construction throughout the length of the boom between the outhaul and the goose-neck fittings;

Fig. 6 is an enlarged view particularly in cross-section of the goose-neck and mast fitting;

Fig. 7 is an end view on the line 7—7 of Fig. 6; and

Figs 8 and 9 are side and end views, respectively, of a modified form of goose-neck fitting.

As shown in the drawings, I have illustrated in diagrammatic form a vessel's mast 1, carrying the roller reefing boom 2, boom crutch 3 at the outhaul end, topping lift 4, and the fragmentary portion of a fore-and-aft sail 5, illustrating the foot 20 of the sail 6, a part of the luff 7, and a portion of the leach 8.

In the particular form of fore-and-aft sail illustrated, a type of typical jib-headed mainsail, or so-called Marconi or Bermuda rig, is designated but it will be understood that a gaff rig or any other suitable form or contour of sail capable of having the lower or foot portion rolled around the boom 2 can be employed advantageously with my improved roller reefing gear.

In the particular form herein illustrated, I have shown the mast 1 fitted with a slide 10 on which slide fasteners 12—12 are arranged, which are secured to the luff 7 of the sail. A tack thimble or cringle 14 is secured to the corner of the foot and luff, and the outhaul or clew cringle 15 is fitted to and secured in the corner between the foot and leach by suitable spacings of the bolt rope and stitching to the sail.

The boom 2, which may be either solid or hollow, and, if hollow, will be sealed at each end where the goose-neck fitting is attached at the mast and where the clew outhaul fittings are secured, such boom having throughout its length at the upper part a groove 20 in which a track 21 is fitted with suitable slides 22 having eyes or raised portions 23 therein below the normal contour of the periphery of the boom 2 so that the foot of the sail 6 when lashed to the portions 23 of the slides 22 will be substantially at a level with the contour of the boom so as to roll smoothly therearound.

As herein shown in preferred form, I may level off the top of the boom, as indicated at 24, and fit thereto a top piece 25 of mahogany, teak, or other hard wood, with rounded corners 26 over which the sail will more readily lie without any danger or damage, forming the groove 20 in this top strip 25.

Referring now to the goose-neck end of the boom structure, I form a shouldered or reduced portion 29 on the outer periphery of the boom to receive a metal casting 30 which encircles the end of the boom and carries on its extreme outer or forward piece adjacent the mast 1 a gear 33. Preferably, also, I bore a central tapered hole from the end of the boom inwardly, as indicated at 34, to receive an inwardly projecting center casting 36 formed integral with the member 30 and gear 33. The interior of this center casting 36 is hollow and provides bearing surfaces 37 and 38 in which fit and rotate bearings 41 and 42 of a shaft 40, on which shaft the boom 2 rotates.

I form this shaft 40 as a casting integral with a hub 50, which extends beyond the gear 33 as 75 a forked member with depending arms 51 and

52, having a bored recess 53 thru the top pair of the forked members to receive a bolt 55; and at the bottom of said arms 51 and 52, I form bearings in the hubs 56 and 57 for the shaft 58 carrying a worm 60 between said hubs 57 and 58, said shaft 58 extending beyond the hubs and being squared to receive a crank 61 with a handle 62 to rotate the same on either end. The worm 60 is splined or otherwise secured to the shaft 58 and is adapted to mesh with the teeth 33 on the 10 castings secured rigidly to the boom 2.

Thus the worm 60 is at all times held in engagement with the gear 33 and will move rigidly therewith when the boom is raised or lowered vertically, which vertical movement is permitted by 15 the bolt 55 acting as a vertical pivot for said boom and the gear connections.

As it is important to have the gear structure as compact as possible to save space between the mast 1 and back cringle 14 of the sail 5, I am 20 enabled to gain some advantage by hollowing or recessing the casting 30 where the gear 33 is formed thereon, as shown at 63, Fig. 6. I also form an encircling flange 65 around the casting 30 to guide the luff 7 against entanglement with 25 the gear 33 as the sail is lowered and the boom rotated, although as previously explained, my construction enables the tack 14 to be so closely positioned to the mast 1 as to be substantially in 30 vertical alignment with the luff of the sail and, hence, the tendency of the sail is to wind up smoothly around the boom and not to drag across the flange 65 or the gears.

To secure the forked members 50, 51, and 52, as well as the axle 40 on which the boom 2 rotates, together I assemble the axle to the casting 30 before fitting the same to the boom. Thus I fit the axle 40 to the central hub 36, assembling these together by having a threaded extension 66 on the extreme end of the axle 40 to extend beyond the center casting 36 and to receive a 40 threaded nut 67, which bears upon a washer 68 spanning the end opening of the center casting 36 and thus hold the axle and its assembled forked member in rotatable contact with the entire end 45 casting 30.

In order to secure the tack of the sail to this fitting 30, I provide in the upper portion a grooved section 69 in which a shackle bolt 70 is secured by a shackle pin 69, which shackle 70 will engage the tack cringle 14 and thus hold the tack of the sail properly in alignment with the top of the boom; and by my construction I am enabled to fit this shackle 70 so close to the mast 1 as to have the luff 7 in alignment with the track 55 fastenings above and with the horizontal pivot below the boom on which the same swings, and which pivotal construction will now be described.

Fitted to the forked hub 50 is the upper portion of my L-shaped goose-neck fastening 71, 60 which is of appropriate width to span the fork between the arms 51 and 52, and is rounded as shown in dotted lines at 72 and bored to receive the bolt 55, which thus supports the hub 50, arms 51 and 52, with the attached worm gear, 65 and the casting 30 and the boom 2 on a vertical pivot. The goose-neck member 71 extends downwardly a sufficient distance to clear the worm 60, and I then expand the same underneath the arm as by an arm 75 to a vertically depending pivot 70 75 fitted substantially underneath the shackle 70 for the tack of the sail and, hence, in alignment with the luff 7. The pin 71 forces the horizontal pivot for the swinging of the boom while the bolt 55 affords the vertical pivot. 75

To support the pivot 77 and, hence, the goose-neck structure I provide an adjustable mast fitting comprising a rearwardly extending bracket 80 with a hub 81 formed to receive the pin 77 of the goose-neck 71, and with a pair of mast-encircling straps 82 and 83 which are suitably folded together by lugs 84 and 85 on the end of each strap and united by bolts 86-86 and nuts 87-87. These may be adjusted about the mast 10 to any desired height to support the boom 2.

I prefer to form the pivot member 77 and the supporting socket 81 as tapered members, as illustrated in Figs. 6 and 7, and provide shouldered extension on the pivot 77 downwardly below the 15 socket member 81, as shown at 87, to be threaded and receive a correspondingly threaded nut 88 to hold the same in assembled position.

Thus it will be seen that by my novel and improved L-shaped goose-neck construction cooperating with the casting 30 and the forked hub member supporting the worm 60, which member is itself, in turn, pivotally supported by the bolt 55 to the L-shaped goose-neck member 71, I have provided an extremely simple, strong, efficient and compact roller reefing gear construction which accomplishes the desirable result of having the pivot 77 and all its attached reefing gear construction substantially in alignment with the luff of the sail.

30 Fitting of the handle 61 to either squared end of the shaft 58 and rotating the worm 60 thereby will thus rotate the boom 2 and either roll up the sail as the hoisting halyard is slackened off, or unroll the sail when the halyard is being set up, 35 keeping the entire foot of the sail at all times smooth and unwrinkled, eliminating all tendency to drag the luff angularly across the gears as it comes down from the mast slides or hoops, or as it is drawn up along the same.

40 Furthermore, the gear can be operated with the boom at any angle on its horizontal pivot 77, either brought off at practically a ninety-degree angle with the keel, or unduly in alignment with the keel as when the boom is resting in the boom crutch 3 and at any angle in between, as well 45 also as when the boom is at any angle vertically either on the pivot afforded by the bolt 55 either with the boom held up by the topping lift 4 or otherwise.

50 In Figs. 8 and 9, I have illustrated a modified form wherein I position the worm 60 to mesh with the gear 33 on the top of same instead of at the lower or bottom portion, and in this modified form I make the goose-neck as a forked member to extend upwardly and span both the worm 60 and the corresponding yoke, comprising arms 90 and 91 formed as a casting with the axle 40. As best shown in Fig. 6, this construction provides the upwardly extending arms 90 and 91 as a rigid 60 expansion of the axle 40, having hubs at the upper ends 92 and 93 between which the worm gear 60 is secured to the crank shaft 58.

This shaft 58 extends beyond the hubs 92 and 65 93 to hubs 94 and 96 formed at the end of U-shaped arms 97 and 98 of this type of goose-neck 100, which has a corresponding tapered pivot pin 101 fitting in the socket 81 of the mast fitting, with a threaded extension 102 secured by a nut 103 corresponding to the horizontal pivot as explained in connection with Figs. 6 and 7.

In this form I provide a somewhat closer positioning of the shackle bolts 71 and flange 65 on the casting 30 to the back of the mast 1, as will 75 be readily appreciated, and the operation of ro-

tating the roller boom thru the worm 60 is identical with that above described.

Referring now to the outhaul construction, which enables the boom to rotate in cooperation with the goose-neck end, I form an outhaul fitting comprising a casting 110 fitted in the recessed and shouldered part of the boom 2 at the 5 outhaul end, with a central troughlike section 112 extending a considerable distance forwardly of the foot end of the boom sufficient to allow the 10 clew outhaul operation. At the forward end of the trough 112 is provided a hub 113, and at the foot end is a corresponding shouldered bearing 114 to receive the forward and aft end, respectively, of the threaded shaft 115, permitting 15 rotation of this shaft with the thrust bearing lengthwise, as shown in Fig. 3.

Fitted on the shaft 115 is a travel member 116 having a threaded socket thru which the shaft 115 passes. At the upper end of the traveler 116 20 is an extension 117 thru which a pin 118 passes to engage an L-shaped shackle 120 adapted to engage the clew cringle 115. Thus, rotation of the shaft 115 will move the traveler 116 inwardly or outwardly and, correspondingly, the clew of 25 the sail loosening or stretching it respectively within the limits of the length afforded by the shaft 115.

I prefer to form the trough 112 with a pair of inwardly extending flanges 121 and also form on 30 the traveler 116 a pair of outwardly extending ridges 122 to bear just underneath these flanges 121 throughout the entire extent of the trough 112 except at an opening 124 to allow assembly, said opening 124 being slightly greater in length 35 than that of the ridges 122 on the traveler 116. Thus the strain of the sail is taken from the traveler to the flanges 121 and thereby relieving the shaft 115 of such stress.

I form the outer end of the shaft 115 squared 40 at 125 to receive the handle of a crank to rotate the same and manipulate the clew outhaul inwardly or outwardly, as desired. I also prefer to form the end of the casting 114 with a rearwardly extending shoulder or reduced portion 128 to 45 receive a circular ring 130, having a depending lug 131 to which a shackle 133 is fitted and which secures the main sheet block, thus permitting the boom to be rotated inside the ring 130 during reefing or unrolling and while the main sheet 50 is secured thereto.

In order to secure the ring 131 in its position I apply a plate 135 having a hollow and inwardly turned portion 136 to fit within the flanged end 114 of the casting. Said plate may, if desired, 55 have its inwardly extending hub threaded into the outwardly threaded part of the shouldered casting 114 and with a central opening to receive the inwardly extending portion of the hub 137 of the boom crutch 3, which boom crutch, in turn, 60 has an enlarged opening 138 to encircle the socketed end 125 of the shaft 115 to permit a crank to be applied thereto and operate the clew outhaul when the boom is in position. Fastening screws 139 may also be provided to secure 65 the plate 135 and rear casting 114 together and prevent loosening of the same.

I may and preferably do form the plate 135 with an inner annular groove in which is secured and fitted a ring 140 assembled therein 70 when the plate 135 is threaded into the shouldered end of the casting 114. This ring is to carry the topping lift shackle 141 and also a locking latch 142 which engages the top 143 of the boom crutch, thereby locking it in posi- 75

tion. For this purpose I extend the upper part of the ring 140 as a U-shaped member 144 thru which a pin 145 secures the latch 142, which latch may be moved upwardly into the U-shaped space afforded by the contour of 144 when the top 143 of the boom crutch is released. At the upper end of this U-shaped member I cast an ear 146 bored to receive the pin 147 of the topping lift shackle 142, all as clearly shown in Figs. 2 and 3.

The boom crutch 3 may be of any suitable form or contour desired, either as a single support or a pair of spanned members, herein illustrated at 3—3 extending downwardly to a fitting 150 on the deck of the boat and permitting swinging action of the legs 3 and the entire boom crutch when the latch 142 is released from the topmost portion 143, as will be readily understood.

Thus I have provided a rotatable reefing gear 20 with cooperating pivotal structure at each end, which enables the slot to be adjusted and fitted by manipulating the clew outhaul either with the boom crutch in position or when the outer end is supported by the topping lift and with the roller operating gears so compactly constructed and arranged as to draw the entire sail smoothly during the rolling operation.

I claim:

1. An improved roller reefing gear of the kind described comprising a rotatable boom, a pivotal support for said boom at the mast end, tack-holding means adjacent the mast end, gear-turning mechanism adjacent the tack-holding means, a goose-neck structure affording a pivot for vertical movement of the boom, and a pivot for hori-

zontal swinging movement of said boom, the horizontal pivot being substantially in alignment with said tack-holding means.

2. In a roller reefing gear construction, a fitting for rigid attachment to the end adjacent the mast on a spar to be rolled, said fitting comprising a vertical pivot construction, a rigid gear, a worm to operate said gear, a pair of links supporting said worm and movable with the spar on said vertical pivot, and an L-shaped goose-neck attached to the said fitting and links, and having a horizontal pivot extending under the said gear and worm closely adjacent the mast, and substantially in alignment with the luff of a sail attached to said mast and to be rolled on said boom.

3. Boom supporting and rotating mechanism of the kind described, comprising a pivotal end fitting for the boom adjacent the mast, a tack-holding fastening to secure the tack of the sail adjacent said end of said boom, a circular gear on the end of said fitting, a central pivot within said fitting on which said boom may be rotated during the roller reefing operation, means holding a worm in mesh with said gear adapted to receive turning cranks at each end, an adjustable mast fitting having a goose-neck pivot spaced from said mast, and an L-shaped goose-neck pivotally supporting the end of the boom in said mast fitting and providing for horizontal swinging movement of the boom on a pivot substantially in alignment with said goose-neck pivot and with the tack-holding means.

BROR TAMM. 35
